UNITED STATES PATENT OFFICE.

CLARENCE E. BLAKESLEE, OF CRANFORD, AND WILLIAM A. AHLGRAN, OF SCOTCH PLAINS, NEW JERSEY.

WINDOW-CLEANING SCRAPER.

1,242,913.

Specification of Letters Patent. Patented Oct. 16, 1917.

Application filed December 18, 1913. Serial No. 807,424.

To all whom it may concern:

Be it known that we, CLARENCE E. BLAKESLEE, a citizen of the United States, and a resident of Cranford, in the county of Union and State of New Jersey, and WILLIAM A. AHLGRAN, a citizen of Sweden, and a resident of Scotch Plains, in the county of Union and State of New Jersey, have invented a new and Improved Window-Cleaning Scraper, of which the following is a full, clear, and exact description.

This invention relates to painters' tools, and has to deal more particularly with scrapers which are intended for use in cleaning paint from window panes, but it is obvious that the tool may be used by others than painters wherever it is required to remove substances adhering to the surface of a pane of glass.

The invention has for its general objects to provide an improved scraper which is comparatively inexpensive to manufacture, thoroughly reliable and efficient in use and of handy design.

More specifically, the object of the invention is the provision of a scraper in the form of a holder consisting of a novel shape of jaws or clamping members in which a sharpened flexible blade is clamped with the sharpened edge projecting out of the jaws, there being a suitable handle connected with the blade holder and extending at right-angles to the scraping edge of the blade so that the tool is used by pushing the same against the paint or other matter to be removed, while the pressure is brought to bear on the tool in such a manner as to press the sharpened edge of the blade approximately flat against the surface of the glass, such position of the cutting edge of the blade being most effective in entering under the paint or other matter to be removed and scale it off the glass.

With such objects in view, and others which will appear as the description proceeds, the invention comprises various novel features of construction and arrangement of parts such as will be set forth with particularity in the following description and claim appended hereto.

In the accompanying drawing, which illustrates one embodiment of the invention and wherein similar characters of reference indicate corresponding parts in all the views,

Figure 1 is a perspective view of the window cleaning scraper; 55

Fig. 2 is a side view thereof;

Fig. 3 is a side view showing the tool in the act of scaling off a lump of paint;

Fig. 4 is a detail sectional view, showing 60 the manner of securing the holder to the handle before the holder is completely formed; and

Fig. 5 is a perspective view of the blade removed. 65

Referring to the drawing, A designates the holder for the blade B which has a cutting edge 1 projecting from one edge of the holder, while secured to and projecting from the opposite edge or back of the holder is 70 a handle C.

The holder A comprises a pair of flexible plates or jaws 2 and 3 which are made from a strip of sheet metal doubled centrally to form a clamp. The upper jaw 2 75 has its free edge bent at a slight angle toward the jaw 3 to form a lip 4, while the lip portion 5 of the jaw 3 is disposed opposite the jaw 4 so as to coöperate therewith and frictionally grip the blade B. In other words, when the blade is inserted the jaws are under tension, since the jaws must be spread apart against their own resiliency when the blade is applied. The blade in width, that is to say from its cutting edge 80 to its back edge, is of greater dimension than the jaws from the lips thereof to the back portion, so that the back edge 6 of the blade will bear against the back or connecting portion 7 of the jaws. It will thus be 85 seen that the blade has a substantial bearing so as to resist pressure which is brought to bear on the blade when the tool is used for removing the paint or other material from a surface. The blade is extremely thin, and 90 hence flexible, and the cutting edge 1 is sharpened to a very acute angle in order that it can more readily enter under a lump or spatter of paint that has hardened on the surface. Thus when the tool is in operation, 95 as shown in Fig. 3, a pressure is brought to bear downwardly on the tool so as to flex the blade and bring the bevel on the under side thereof at the cutting edge practically flat against the surface from which the material is to be removed.

The blade holder A is provided with a handle C of any suitable construction, the

axis of which is substantially at right-angles to the cutting edge of the scraper. In the present instance the handle is made of a piece of wire 8 doubled on itself in the form of a loop that can be conveniently grasped in the hand, the loop being narrowed at 9 and the extremities of the wire diverging therefrom so as to be connected to the handle A near the ends. The ends 10 of the wire are secured by rivets 11 to the upper jaw 2 of the blade holder. The blade holder is fastened to the handle before the handle is completely formed, as shown in Fig. 2, and after the parts are riveted together the lower edge 3 of the holder is bent from the full to the dotted line position, Fig. 4. The portions 12 and 13 of the handle are so disposed as to form rests for the end of the thumb and for the index finger of the hand in which the holder is held, whereby a considerable pressure can be applied to the tool to remove the paint or other material without becoming tired. The blades of the tool are so inexpensive that a new one can be substituted for a dull one, and hence no attempt is made to adjust the position of the blade, as would be necessary if the same were to be sharpened from time to time.

It will be understood that the handle C is secured to one side or jaw of the blade holder and projects rearwardly in substantially the plane thereof or straight, as shown in Figs. 2 and 3, so that not only can the blade be applied to the glass at a very acute angle thereto, without the handle or its attachment to the blade holder striking the glass or interfering therewith, but also the handle transmits the pressure against it to push the device forward with maximum rigidity, so that the handle can be made of much lighter material than if there were bends or turns in it. Furthermore, it will be noted that the handle lies upon the outside of one of the jaws and projects therefrom without engagement with the rear edge of the holder or with the opposite jaw, so that the doubled sheet metal portion is left perfectly free in its tensional holding of the blade, so far as the handle is concerned. Also it will be noted that the handle is secured to the jaw 2 which bows, between its rear and front edges, away from the blade 5 and other jaw 3, and said bowed jaw being the upper one the handle is attached to the upper jaw so that in use the lower jaw is free to bend or flex as clearly shown in Fig. 3. In this way the most

effective use of the tool is obtained and the strain of pressure does not tend to separate the handle from the jaws as it would if the handle were secured to the under jaw.

From the foregoing description taken in connection with the accompanying drawings, the advantages of the construction and method of operation will be readily understood by those skilled in the art to which the invention appertains, and while we have described the principle of operation, together with the device which we now consider to be the best embodiment thereof, we desire to have it understood that the device shown is merely illustrative, and that such changes may be made when desired as are within the scope of the appended claim.

Having thus described our invention, we claim as new and desire to secure by Letters Patent:

In a device of the character described, the combination of a blade holder comprising a sheet of metal doubled to form jaws of a single thickness of sheet metal tensioned toward each other and adapted to receive between themselves a blade so that the same projects at its front edge from between the front edges of the jaws and seats at its back edge against the line of doubling of the sheet of metal, one of said jaws being bowed away from the other so as to be spaced between its front and rear edges from the blade, and a handle comprising a piece of wire doubled to form a hand grip and having its adjacent ends laid flatwise upon the outer side of said bowed jaw of the holder and secured thereto near the ends thereof so as to project away from the holder with the rear edge and opposite jaw of the holder left free and the tension of the jaws unimpaired to grip the blade.

In testimony whereof I have signed my name to this specification in the presence of two subscribing witnesses.
